UNITED STATES PATENT OFFICE.

LOUIS SANDERS, OF NEW YORK, N. Y.

DESIGN FOR A BELT.

SPECIFICATION forming part of Design No. 32,891, dated June 26, 1900.

Application filed May 26, 1900. Serial No. 18,166. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is a full, clear, and exact description, reference being had to the accompanying drawings, forming 5
10 a part thereof, in which—

Figure 1 is a plan view of the body portion of a belt embodying the features of my design. Fig. 2 is a transverse section taken on the line 2 2 of Fig. 1, and Fig. 3 is a central transverse 15 section taken on the line 3 3 of Fig. 1.

The leading features of the design consist in the approximately diamond shape of the central portion A of the body, upper and lower continuous cord-like lines B, following the 20 side marginal contours of the body, and a cen-

tral cord-like line C, having a skeleton diamond formation D at the central portion of the body.

A minor feature of the design consists of angular cord-like lines E between the central diamond figure and adjacent continuous lines, which lines E are in harmony with adjacent lines at the central portion of the body. 25

Having thus described my invention, I claim as new and desire to secure by Letters 30 Patent—

The design for a belt herein shown and described.

In testimony whereof I have signed my name to this specification in the presence of 35 two subscribing witnesses.

LOUIS SANDERS.
